SPEED GOVERNOR FOR INTERNAL-COMBUSTION ENGINES

Filed Jan. 13, 1943

UNITED STATES PATENT OFFICE

2,375,479

SPEED GOVERNOR FOR INTERNAL-COMBUSTION ENGINES

Louis Langhaar, Mount Olive Township,
Morris County, N. J.

Application January 13, 1943, Serial No. 472,229

6 Claims. (Cl. 137—152)

My invention relates to the class of devices used for governing or limiting the speed of internal combustion engines, more particularly in motor vehicles, and an object of my invention, among others, is to provide a governor simple in construction, that may be readily installed for use in conventional commercial engines as easily as a gasket, that may be readily adjusted for various speed limits when installed in an engine, that shall be particularly effective in maintaining engine power and performance up to any desired speed limit, and that shall provide as accurate engine speed control as is practical under operative traffic conditions. My governor belongs to the class commonly called "air-velocity" governors in which the valve is actuated by the force of the intake air resisted by calibrated spring force, which spring force reopens the governor valve below the desired governed speed limit.

One form of a governor embodying my invention and in the construction and use of which the objects herein set out, as well as others, may be attained, is illustrated in the accompanying drawing, in which—

Figure 1 is a side view of a portion of an engine equipped with my improved governor.

Figure 2 is a view in central lengthwise section through the supply tube for fuel to an engine and showing my improved governor secured therein, the governor valve being open.

Figure 3 is a similar view showing the governor valve closed.

Figure 4 is a view similar to Fig. 2 but looking at the governor from a point at right angles to the point of view of Figure 2.

Figure 5 is a view in section on a plane denoted by the broken line 5—5 of Fig. 2.

Figure 6 is a view similar to Figure 2, but showing a modification.

My present invention is an improvement upon the governor forming the subject matter of patent to me No. 2,187,243, dated Jan. 16, 1940, for the purpose of providing external adjustment with the governor in use in a conventional commercial engine as above stated and for better engine power and performance than obtained with the device of Patent 2,187,243.

In the accompanying drawing the numeral 8 denotes a motor that may be of any ordinary construction of the internal combustion type, 9 the exhaust manifold, 10 the intake manifold, 11 the carburetor and 12 the fuel supply tube extending from the carburetor to the intake manifold, all of which parts may be of ordinary and well known construction and which also include a throttle arm 13 secured to the shaft 14 of a throttle valve 15 located to control the passage in the tube 12 between the carburetor and manifold 10. A throttle rod 16 connected at one

end with the arm 13 extends to any suitable location or device for operating the throttle valve 15.

As a matter of convenience and economy I so construct my improved device that it may be made at a minimum cost and may be readily attached to motor equipment in common use, such device, as hereinbefore mentioned, being located inside of the engine fuel intake 12 and comprising 5 a case 17 of tubular form and preferably having a flange 18 extending in position to be secured between the flanges 19—20 at the adjacent ends, respectively, of the fuel supply tube 12 and the part 21 thereof projecting from the carburetor 11. The base 17 is rounded as at 22 at the entrance end thereof to increase the efficiency of the air flow.

My improved governor valve 23 is pivotally mounted on a shaft 24 in the case 17 preferably 20 at one side of the diametrical center of said case, as shown in Figs. 2 and 3 of the drawing. This valve is bent at or near such pivotal mounting with the incident end thereof being angularly disposed to the direction of air flow and the 25 discharge end more nearly in the direction of air flow with the valve in its open position as shown in Figs. 2 and 6 of the drawing. By "bent" I refer to form and not method of fabrication. By this construction the valve offers extremely slight air

25 resistance on the discharge end when open, providing efficient air flow with corresponding engine performance. A spring 25 is attached to the valve and operates to retain it in open position against a stop 34, as shown in Figure 2 of 30 the drawing. The arms 27—28 of the spring 25 may be attached in any of a series of holes 30 in part 29, and holes 31 in part 32, as shown in Fig. 2 of the drawing, for varying the leverage of the spring 25 on the valve 23 for different engine speed adjustments thereof. A relatively light 35 spring 26 which is adjustable in spring support 29 by means of screw 33, one end of said spring being attached to the valve 23, is also shown as a corrective for spring 25 as a means of improved 40 precision over a wide range of engine speed adjustments. I do not limit myself to any special form or forms of springs, the forms shown being of simple design. The spring support 29 is attached to the case 27 as shown in Figs. 2, 3 and 6, the stop 34 being a part of the support 29. Holes 31 are in plate 32 attached to valve 23. I do not limit myself to these specific forms and 45 details of adjustment of spring leverage which are shown for simplicity.

In the form of the device shown in Fig. 6 the parts are of the same general construction as that shown in the preceding figures and as hereinabove described, with the exception that the spring 25 is omitted and an externally adjustable spring is used as hereinafter described. This ex- 50 55 60

ternally adjustable spring 35 is arranged to be adjusted outside of the tubes for supply of fuel to the engine, as shown in Fig. 6, in which spring 35 has an arm 36 connected at one end to the valve 23 below the pivot 24 and another arm 37 connected with a threaded rod 38 extending outwardly between the flanges 19-20, the outer end of the rod being threaded for an adjusting nut 39, any suitable way being arranged for the rod to pass between the flanges, but I show a convenient way in which to illustrate. Any suitable arrangement of parts may be used for obtaining external adjustment provided a joint in the engine air intake conduit is utilized for the purpose and thereby adapting said adjustment means for use in a conventional commercial engine.

Figure 3 shows the valve in a closed position, the word "closed" merely signifying some closed position whatever that may be and not necessarily airtight. In moving from the open position of Fig. 2 to the closed position of Fig. 3, the leverage of the spring 25 on the valve 23 decreases because the leverage is moving toward dead-center, "dead-center" being a term understood by all skilled mechanics and signifying a position wherein the leverage is zero. The word "leverage" is used correctly, and does not mean "moment" which is the leverage multiplied by the force. Likewise in Fig. 6, as the valve moves toward closure the leverage moves toward dead center, being in both cases decreasing leverage as the valve moves toward closure. Various structural considerations of space, simplicity and avoidance of undue air impedance influence this choice of construction. By careful utilization of aerodynamic principles in making the valve 23 I have found it practical to eliminate the spring 26 completely and yet obtain desired accuracy of engine speed control by use of such decreasing leverage on the springs 25, 35, or equivalent; and I prefer and claim such simple construction while merely disclosing the construction with the spring 26 as a practical arrangement if desired.

I am aware that a bent valve is not new per se, and that a spring or springs acting with decreasing leverage as the valve moves toward closure is not new per se and is shown in my patent of record noted herein. The combination of a bent valve, hereinbefore defined, and a spring or springs acting with decreasing leverage as stated is new and produces new and valuable results. All governors operating by the force of the intake air offer some air impedance having some adverse effect on engine performance, and I have found that with this new combination of parts it becomes practical to operate the valve with such slight air and spring force that air impedance becomes operatively negligible throughout the governed speed range. Various vehicle drivers have reported no observable difference in performance up to a given speed limit with or without my improved governor being installed in the engine. It is always to be considered that my improved governor is intended primarily as an article of commerce adapted for use with a conventional engine without special provision therefor.

This application is a continuation-in-part of my co-pending application filed September 3, 1941, of Serial Number 409,390.

I claim:

1. A self-contained governor for influencing flow of air through a conduit, said governor comprising a carrier, a pivotally mounted unbalanced butterfly valve to be closed solely by the air cur-

rent passing through said conduit, and a spring to hold said butterfly valve normally open below some pressure thereon, said butterfly valve and spring being mounted in a carrier and adapted for insertion as a unit within said conduit, said carrier being provided with a flange for mounting the carrier in the conduit and forming with said carrier a converging air passage.

2. A self-contained governor for influencing air flow through a conduit, said governor comprising an unbalanced butterfly valve urged toward closed position by the air flow through the conduit and normally held open by spring means, a stop to limit opening movement of the valve, said butterfly valve, stop and spring being mounted in a carrier and adapted for insertion as a unit within said conduit, said carrier being provided with a flange for mounting the carrier in the conduit and forming with said carrier a round-edged air entrance.

3. As an article of commerce adapted for use with a conventional internal combustion engine, said engine having an air intake conduit with a joint, a governor for influencing air flow through said conduit, said governor comprising an unbalanced butterfly valve urged toward closed position by air flow through said conduit, a spring located within said conduit to yieldingly resist such closing movement, and means associated with said spring arranged to adjust its force upon said valve, said means passing through said joint to the outside of the conduit.

4. As an article of commerce adapted for use with a conventional internal combustion engine, said engine having an air intake conduit with a joint, a governor for influencing air flow through said conduit, said governor comprising an unbalanced butterfly valve urged toward closed position by the flow of air through the conduit, and normally held open by means including a spring for exerting a yieldable force on said valve in opposition to the force of the air flow, said means including mechanism extending through said joint and constructed and arranged to adjust said force from outside said conduit.

5. As an article of commerce adapted for use with a conventional internal combustion engine, said engine having an air intake conduit with a joint, a governor for influencing air flow through said conduit, said governor comprising an unbalanced butterfly valve urged toward closed position by the flow of air through the conduit, and normally held open by resilient means for exerting a yieldable force on said valve in opposition to the force of the air flow, said means including mechanism extending through said joint and constructed and arranged to adjust said force from outside said conduit.

6. In combination with a conduit for combustion air intake of an internal combustion engine, a governor comprising a pivotally mounted check valve and a spring operatively acting thereon, a flanged case having a rounded edge orifice and adapted to be secured between the flanges of abutting ends of said conduit for locating said spring and valve in said conduit, said spring being arranged to hold said valve open below some determined intake air velocity and to permit closure at some higher velocity for governing engine speed according to the amount of valve closure, said spring being also arranged to operate on said valve to increase the closure resistance thereof at a faster rate than the amount of motion of said valve.

LOUIS LANGHAAR.
